UNITED STATES PATENT OFFICE.

JOSEPH G. GORDON, OF BIRMINGHAM, ALABAMA.

BARBECUE-FURNACE.

1,156,773.

Specification of Letters Patent.

Patented Oct. 12, 1915.

Application filed August 26, 1915. Serial No. 47,492.

To all whom it may concern:

Be it known that I, JOSEPH G. GORDON, a citizen of the United States, residing at Birmingham, in the county of Jefferson and State of Alabama, have invented certain new and useful Improvements in Barbecue-Furnaces; and I do hereby declare the following to be a full, clear, and exact description of the invention, such as will enable others skilled in the art to which it appertains to make and use the same.

This invention relates to summer or camp stoves of the knockdown type; and the object of the same is to construct a portable folding stove or furnace for camp or field use, made usually of a size to receive a side or a quarter of beef for instance, so that it could be stored in small compass, easily transported, quickly set up, and used for camping or military purposes.

Further objects will appear in the following specification which sets forth the preferred manner of constructing this device, reference being had to the accompanying drawings wherinc—

Figure 1 is a side elevation with certain doors swung open, Fig. 2 is a longitudinal section on the lines 2—2 of Figs. 3 and 4, and Fig. 3 is a cross section on the lines 3—3 of Figs. 1 and 2. Fig. 4 is a plan view. The cover is omitted from all views except Fig. 1. Fig. 5 is a perspective view with certain panels and doors turned aside and the interior elements omitted, so as to show the skeleton framework. Fig. 6 is a perspective detail of the lining and part of the grate. Fig. 7 is a sectional detail on the line 7—7 of Fig. 5, and Fig. 8 is a perspective detail of one corner.

This device is by preference made entirely of metal, and while its size may be such that it would accommodate a side of beef as suggested, it is quite possible to make it either larger or smaller, although if larger it would not be so easily stored and transported. The precise metal employed, and the proportions and exact details of construction of parts are susceptible of considerable modification, excepting as set forth in the claims; and while I intend to use this stove or furnace out of doors, it is quite possible to set it up permanently and use it indoors. Broadly speaking it includes the ordinary elements of a cooking stove such as a grate G above an ash-pit A and beneath a fire-pot P, an oven O, and a stack or chimney C

for the outlet of the products of combustion. Above the fire-pot is a screen S, and above the screen in turn is a grease rack R—these being the only elements which separate the fire-pot from the oven. The whole is inclosed within a surrounding wall W having suitable doors D, the fire-pot is surrounded by a lining L, and a skeleton framework F stands between the wall and lining and supports all parts. The top T is preferably made dome-shape and removable.

While I will describe these various parts as I prefer to construct them, I lay no claim to much of the detail thereof.

The skeleton framework F is best seen in Fig. 5. It is made up of four posts 1, preferably hollow and about an inch square, and these may be mounted on legs or driven into the ground at their lower ends although I prefer to form them with feet 2 at this point, the feet resting directly on the ground or perhaps on stones set into the ground as seen in section in Fig. 3. Each post has two perforated ears 3 near its lower end and two others near its upper end, and the ears of the several posts are connected by top and bottom side bars 4 and top and bottom cross bars 5, all bars preferably having right-angular hooks 6 at their extremities which removably engage the perforations in the ears.

The wall W is herein shown as made up of a solid panel 10 at the left side of the stove, a single panel 11 across the rear of the stove, a third panel 12 covering the lower half of the right of the stove, and a fourth panel 13 covering the upper portion of the front of the stove; and all these panels are connected end to end by hinges 14 whose pintles 15 may be removable so that the various parts can be readily disconnected if desired, although the wall just described and the doors yet to be described might be folded together accordion-like if preferred. At suitable points the panels are provided with holes 17 registering with others, 7, in the posts, and through these holes may be passed pins 18 headed at one end and slotted near the other end as at 19 for the reception of keys 16. By this or equivalent means the panels of the wall are detachably fastened to the framework.

The doors D are those usually employed on a stove, as for instance the ash-pit door 20, the fire door 21 above it, both these hinged to the front edge of the left wall as

shown; and the oven doors 22 and 23 hinged respectively to the panels 13 and 11 and adapted to close against a stop 24 rising from the panel 12 and to be fastened closed by a latch 25 and catch 26. The other doors 20 and 21 may also have latches 25' engaging catches 26' on the panel 12 as shown. The top T is preferably dome-shaped as seen at 27 in Fig. 1, has handles or handles 10 holds 28 at suitable points, and has a depending skirt 29 which preferably passes down inside the wall and the oven door and therefore will not interfere with the opening of the latter or with the entire removal of the 15 top when desired.

A lining L of sheet metal is provided around the lower portion of the stove excepting across its front. It comprises two side plates 30 having their upper edges inclined 20 forward and notched as at 31 and their lower corners notched as at 32 to pass over the lower front cross bar 5, and above these notches are holes 37 registering with those numbered 7 in the front posts so that they 25 will receive fastening pins 18 for holding these plates in place at their front ends. The lining also comprises a rear plate 33 having lips 34 turned forward from its edges around the rear ends of the side plates, 30 preferably also having brackets 35 engaging the inner faces of said rear ends; and this rear plate has an opening 38 with a flange 39 up both sides and across the bottom of the same for a purpose to appear. To the inner faces of the side plates are secured longitudinal cleats 36 as best seen in Fig. 6.

The grate G is a composite affair susceptible of removal, especially when its bars need to be changed to adapt it to various 40 kinds of fuel, for it is possible to use wood, coal, coke, or other fuels in this stove. Cross bars 45 are passed through alined holes 47 in the side panels of the wall and the side plates of the lining and may have hooks or 45 heads 44 at one end and be slotted for keys 46 at the other end as seen in Fig. 3. There are by preference two of these cross bars, and upon them are laid A-shaped bars or beams 40 having feet 41, there being one 50 beam along inside each side plate of the lining as seen in Fig. 3. Overlying the apexes of these beams are the grate bars 42 which may also be of sheet metal and of A-shape as seen in Fig. 2, although these bars could 55 be changed as above suggested. The composite grate as thus built up upon and supported by the cross bars 47 defines the ash-pit A beneath it, and the fire-pot P is above it.

60 The screen S overlies the fire-pot, and is composed of a sheet 50 which is arched as best seen in Fig. 3, its edges resting removably within cleats 36. By preference another screen 51 is secured to the inner face 65 of the rear panel 11 as seen in Fig. 5, and be-

hind this screen said panel is carried out to the rear in a flue 52 whose lower end is bevelled as at 53 and opens into the rear of the fire-pot beneath the screen 51, while the upper end of the flue has an extension 54 constituting the chimney C and possibly carried to a greater height by means of a stack if desired and as indicated at 55 in Fig. 1. Thus one of the screens forms an arch over the fire-pot P and separates it from the oven 75 O which is inclosed within the wall W above the lining L and opposite the oven doors; while the other screen separates the oven at its rear from the open front side of the flue 52. The netting of which these screens are 80 made should be of such material and mesh as to prevent the passage through them of flames, smoke, and gases which will injure the food being cooked within the oven, but will not prevent the passage of heat. 85

The grease rack R forms an important feature of this invention. Its body is made up of a number of V-shaped troughs 60, each having horizontal flanges 61 along its upper edges and shaped so as to rest at its ends 90 in the notches 31 of the side plates of the lining. The left wall panel 10 carries a pair of brackets or supports 62 on which rests a collecting trough 63 standing between this wall and the left lining plate 30 as best seen in 95 Fig. 5, and the lower ends of the troughs 60 deliver into this collecting trough 63. I should have said that the right hand lining plate is a little wider or at any rate its notches 31 are a little higher than those in 100 the left hand plate, with the result that the other ends of the troughs 60 are higher as seen in Fig. 3, and these ends are closed as at 64 and preferably have flanges 65 that drop down behind this plate as seen in this 105 view. The wall 10 has a hole 67 at a proper point, and through this hole may be passed a pipe 68 which has a threaded or other removable engagement with a corresponding hole in the collecting trough 63, the pipe 110 having a cock 69 as shown.

With the above construction of parts, this knock-down stove may be stored and transported in its folded condition, and when it is desired to put it into use the posts are first 115 set up and connected by the cross bars to make up the skeleton framework F as shown at Fig. 5. The various panels of the wall W are then passed around this framework and pins 18 inserted and keyed. The collecting 120 trough 63 is then laid on the supports 62 and the pipe 68 applied. Next the lining L is put in place and the rear ends of its side plates engaged between the lips 34 and brackets 35, while their holes 37 are engaged 125 with the appropriate pins 18. The lower cross bars 47 are now run into place and keyed and the composite grate G is laid; then the arched screen S is put into place as seen in Fig. 3, and next the troughs 60 are dropped 130

into the notches to make up the rack R. Now when the top T is applied the stove is complete and ready for use, although at certain times it may be found desirable to add a stack 55 to the flue extension 54 in order to get a good draft, or in any equivalent way connect the extension with a chimney. If the posts have feet 2 they may rest flat on the ground, although probably it will be desirable to rest them on stones upon or sunk into the ground as indicated in Fig. 3, and build up the earth against the side panels 10 and 12 and the rear panel 11 as any camper will understand. The fire door 21 is now opened, and fuel fed through it onto the grate; and the ash door 20 may be opened sufficiently to admit air for combustion. The fire burns within the fire pot P and products of combustion pass straight to the rear under the arched screen 50, into the lower end 53 of the flue 52, upward within the latter behind the rear screen 51, and out the stack or chimney; and meat or other food placed in the oven O upon the rack R can be cooked without being smoked or tainted with the gases of combustion. Meanwhile its grease and juices will drop into the troughs 60 and run down them into and collect within the main trough 63 whence they can be withdrawn from time to time through the pipe 68 by opening the cock 69. The lining L serves several functions. It not only jackets the fire pot along both sides and across its rear end and thus prevents the escape of much of the heat generated by the fire; but it serves as a support for the grease rack R and its cleats serve to support the arched screen 50, both of which elements intervene between the fire and the food being cooked. The absence of any lining in the upper portion of the body gives the latter additional capacity, and it is quite possible to transport a stove of this character whose oven is large enough to receive a side of beef. I have suggested that the top 27 be of dome-shape as shown, but this is not important and in fact the top could be flat so as to warm dishes or articles on the top of the stove. Other modifications in unimportant parts of the whole may be made without departing from the principle of the invention.

What I claim is:

1. A knockdown stove comprising a skeleton framework including corner posts having holes; a wall consisting of a panel across the upper portion of the front, a full panel at one side, a full panel at the rear having an outlet for the products of combustion, a panel across the lower portion of the remaining side, certain of said panels having holes registering with those in the posts, pins detachably engaging said holes, detachable connections between the panels where they meet, oven doors closing the space above the

smaller side panel, and other doors closing the space below the front panel; a grate raised above an ash pit, a transverse member above the grate between the fire pot and oven, and a top above such oven. 70

2. A field stove comprising a skeleton framework, a wall made in panels surrounding and detachably connected to said framework, certain of such panels being hinged whereby they serve as doors and the rear panel having an upright opening with flanges along its sides connected to constitute a flue communicating with the interior of the stove, a screen across the upper portion of said flue, a grate within the stove, and a screen supported therein and arched over said grate to cover a fire pot which communicates at its rear end with said flue. 75

3. A knockdown stove structure comprising four upright posts each having perforated ears near its upper and lower ends, top and bottom side and cross bars having hooked extremities removably engaging said ears, a surrounding wall made up of panels detachably connected with each other, certain of them being hinged to serve as doors, means for detachably securing the panels to the posts and for fastening the doors when closed, and a top having a skirt fitting inside the upper edge of the wall. 80

4. A knockdown stove structure comprising four upright posts each having perforated ears near its upper and lower ends, top and bottom side and cross bars having hooked extremities removably engaging said ears, a surrounding wall made up of panels detachably connected with each other, certain of them being hinged to serve as doors, means for detachably securing the panels to the posts and for fastening the doors when closed; a lining made up of side plates adapted to stand inside said posts and a rear plate having means at its ends to detachably engage the rear ends of the side plates, means for detachably securing the front ends of the side plates to the front of the posts, and a top whose edges engage the wall. 100

5. A knockdown stove comprising a skeleton framework, a wall inclosing the same and having doors, a lining within the framework along the sides and across the rear end of the stove and rising for substantially half the height of the wall, the rear panel of the lining having an outlet flue, a grate within the lining, and an element across the top of the lining dividing the fire pot from the oven. 115

6. A knockdown stove comprising a skeleton framework, a wall inclosing the same and having doors, a lining within the framework consisting of side plates having notches in their upper edges and a rear plate connecting the rear ends of the side plates and itself having an outlet flue, a grate support- 125

- ed within the lining across its lower portion, and a grease rack made up of troughs within the wall and resting in the notches of the lining and delivering at a common point.
- 5 7. A knockdown stove comprising a skeleton framework, a wall inclosing the same and having doors, a lining within the framework consisting of side plates having notches in their upper edges and a rear plate connecting the rear ends of the side plates and itself having an outlet flue; a grate supported within the lining across its lower portion, and a grease rack including a number of transverse troughs resting in said notches
- 10 and having one end closed, a collecting trough extending beneath their other ends and standing between the lining and the adjacent wall, and a manually controlled outlet for the collecting trough.
- 15 8. In a cooking stove, the combination with the shell having cleats along its sides above the grate, the upper portion of the shell constituting the oven; doors for permitting access thereto, other doors opening

through the front of the shell into the fire pot and ash pit, and a smoke flue opening through the rear of the shell; of a screen arched over the fire pot and dividing it from the oven, its edges being removably engaged by said cleats.

30 9. In a cooking stove, the combination with the shell inclosing a grate, the upper portion of the shell constituting the oven, doors for permitting access thereto, other doors opening through the front of the shell into the fire pot and ash pit, and a smoke flue opening through the rear of the shell; of an arched screen whose edges are secured to the shell above the grate, a grease rack extending across the shell above the screen, and another screen over the outlet flue above said rack.

35 In testimony whereof I affix my signature in presence of two witnesses.

JOSEPH G. GORDON.
